UNITED STATES PATENT OFFICE

CARL J. WARNE, OF ELKHART, INDIANA, ASSIGNOR OF ONE-HALF TO CHARLES C. COLBERT, OF ELKHART, INDIANA

MERCURY SWITCH THERMOSTAT

Application filed February 1, 1932. Serial No. 590,003.

My invention relates to a thermostat having thermometric characteristics for the remote control of various types of apparatus, such as oil burners, furnaces, mechanical refrigerators and the like, and more particularly to one incorporating a mercury switch structure which is featured by a more efficient operation over a longer period of time than is now obtainable with thermostats of standard construction.

One object of my invention is to devise a thermostat of the character indicated in which the electrical circuit is completed through the switch by a member located within the switch container and adjustably held in any desired position by an externally located, magnetic member.

A further object is the provision of a mercury switch thermostat having a thermometer tube in which contact of the mercury with the adjustable member for any position thereof is determined by the position of the mercury in the tube in response to external temperature conditions, the adjustable member having a part extending within the tube for contact with the mercury.

A further object is to embody in a mercury switch thermostat having a thermometer structure an arrangement for positively determining the initial or zero position of the mercury in the capillary tube and to vary such position as desired, thus providing in conjunction with the adjustable member a further means for varying the operating characteristics of the instrument in respect of the temperature at which it functions and the time required at any given temperature for the mercury to rise in the tube until it contacts with the adjustable member.

A further object is to provide a thermostat of the type set forth for use under temperature conditions in excess of those to which a mercury thermometer is normally exposed through filling the container of the switch with a gas at a sufficient pressure to raise the boiling point of the mercury.

My invention is primarily intended to provide an improved type of mercury switch for thermostatic purposes, such as the remote temperature control of various kinds of ap-

paratus, including oil burners, furnaces, mechanical refrigerators and the like. One portion of the switch comprises a thermometer tube which may be calibrated according to any temperature scale and within the capillary tube of which is mounted an adjustable part which is contacted by the mercury as it rises in the tube, or loses contact therewith as it falls, by reason of changes in the temperature to which the instrument is exposed. Preferably, the adjustable part is moved and held in any adjusted position by a magnet of some form, whether of the permanent or of the electro-magnet type, and it is also contemplated that an additional device may be incorporated in the thermostat for positively determining the initial or zero position of the mercury in the capillary tube. The association of the two indicated arrangements provides for a wide range of adjustment of the thermostat and so renders it adaptable for use under a wide variety of conditions.

These and further objects of my invention will be set forth in the following specification, reference being had to the accompanying drawing, and the novel means by which said objects are effectuated will be definitely pointed out in the claims.

In the drawing:

Fig. 1 is an elevation, partly in section of my improved thermostat, as it is viewed from the scale reading side thereof.

Fig. 2 is a sectional elevation of the thermostat taken generally along the line 2—2 in Fig. 5, looking in the direction of the arrows.

Fig. 3 is a section along the line 3—3 in Fig. 1, looking in the direction of the arrows, and showing the manner in which the thermometer tube is formed in the mercury switch container.

Fig. 4 is a section along the line 4—4 in Fig. 1, looking in the direction of the arrows, and showing the relation of the pole portions of the magnet to the switch container.

Fig. 5 is a section along the line 5—5 in Fig. 2, looking in the direction of the arrows, and showing the relation to, and the manner of guiding, the adjustable part within the switch container.

Fig. 6 is a sectional elevation of the lower portion of the thermostat, corresponding generally to the lower portion of Fig. 2, and showing a modified construction whereby the initial level of one of the mercury pools may be adjusted.

Fig. 7 is an enlarged section along the line 7—7 in Fig. 6, looking in the direction of the arrows, and showing the mechanism for varying the mercury level.

Referring to Figs. 1 to 5, inclusive, the numeral 10 designates the container of the mercury switch portion of the thermostat, which is generally elongated in shape and which may be composed of any of the glasses now used for mercury switches, the precise nature of the glass forming no part of my invention.

The container 10 is provided with a lower end wall 11 and is pinch-sealed at the opposite end, as at 12, in the customary manner. A wall 13 divides the interior of the container 10 into chambers 14 and 15, lower and upper, respectively, as the thermostat is viewed in Fig. 3, and said chambers receive, respectively, pools of mercury 16 and 17, said pools having a predetermined depth, as determined by operative conditions. A portion 18 of the wall 13 defines with the adjacent wall of the container 10, a capillary tube 19 and said wall portion 18 is preferably parti-cylindrical in cross section, as shown clearly in Fig. 5, for a purpose hereinafter explained. The exterior of the portion of the container wall 10 adjacent the capillary tube 19 may be calibrated according to any well-known temperature scale, or in any other manner, as indicated generally by the numeral 20 in Fig. 1.

Extending through the end wall 11 are lead-in wires 21 and 22, the material composing these wires being that which is usually employed for a like purpose, such as domet wire and otherwise of similar characteristics, and the character of the seal between these lead-in wires and the glass container being such as to prevent leakage at the indicated points and said conductors being also preferably arranged, as regards their composing materials, that they are characterized by substantially the same coefficient of thermal expansion as the material forming the container 10. An electrode 23 is suitably connected to the lead-in wire 21 within the lower chamber 14, while the lead-in wire 22 extends upwardly through a glass insulating sleeve 24 which is fused at one end to the wall 11 and at the opposite end to a portion 25 of the wall 13, so that the lead-in wire 22 is completely shielded from contact with the mercury pool 16. The wire 22 extends through the wall portion 25 and within the upper chamber 15 has attached thereto an electrode 26 which is at all times completely covered by the mercury pool 17, just as the electrode 23

is always covered by the mercury pool 16. The precise materials of which said electrodes are composed form no part of the present invention, since standard practice may be adopted in this respect, although it is contemplated that in any case the material selected will be such as to offer resistance to the erosive effect of the electric arc.

A sleeve 27, having generally a crescent-like cross section, as shown in Fig. 5, is mounted within the upper chamber 15. The skirt portions 28 and 29, defined generally by the large and small radii of the crescent formation, are joined at their upper ends by the top portion 30, while the lower ends of these portions are always immersed in the mercury pool 17. The skirt portion 29 closely fits the parti-cylindrical shape of the wall portion 18 and is guided thereby in its vertical movement, while also being held against separation therefrom in lateral directions. A portion of the top 30 projects above the upper end of the capillary tube 19 and carries the fine wire 31 which projects downwardly through an aperture 32 provided in the wall 13 and also downwardly into the capillary tube 19. The sleeve 27 is preferably formed of a material having a relatively high magnetic permeability, such as nickel iron or equivalent material, or alloys formed of such materials, while the wire 31 may be composed of a material similar to that comprising the electrodes 23 and 26, for, as will be presently shown, the electrical circuit between the electrodes 23 and 26 is broken at the lower end of the wire 31.

It will be understood that, prior to the pinch-sealing of the end 12, the interior of the container 10 will be exhausted, including the chambers 14 and 15, in accordance with standard practice and afterwards filled with one of the gases which are usually employed for the purpose of substantially suppressing the electric arc which tends to form when a circuit is made or broken in the switch. Many favorable results flow from the use of such gases, such as a marked improvement in the heat conducting characteristics within the container, protecting the wire 31 from deterioration arising from ionization or from whatever cause, arresting the wetting or amalgamation of the wire 31 by the mercury, and of keeping the wire surface clean at all times.

In order to shift and maintain the sleeve 27 in any adjusted position, it is contemplated that a magnet 33 will be employed, said magnet having pole pieces 34 and 35 which closely fit the exterior of the container 10 and are mounted to slide freely therealong. In the drawing, the magnet 33 is denoted as being of a common bar type, although it will be understood that any electro-magnet may be employed, the magnet 33 being intended to illustrate generically any magnetic means

for securing the desired shifting of the sleeve 27.

In the use of my improved thermostat, the lead-in wires 21 and 22 will be connected to some form of electrical circuit whose operation it is desired to control by the thermostat. The precise nature of this external circuit forms no part of the present invention, but for purpose of illustration, it may be briefly stated that they find their counterpart in any of the present oil burner installations, or mechanical refrigerators, furnaces, and apparatus generally where some form of temperature control is desired.

Assuming that the sleeve 27 has been raised until the lower end of the wire 31 is clear of the mercury in the tube 19 and has been placed in a position determined by some convenient reading of the scale 20, and, further, that the thermostat is being employed in connection with a circuit wherein a rise of temperature will require the happening of a certain condition in the external circuit, then with the sleeve 27 occupying the indicated position, it will be obvious that an electrical current cannot flow between the electrodes 23 and 26 for the circuit is broken within the switch by reason of the separation of the wire 31 from the mercury pool 16. However, as the external temperature continues to rise, the mercury will rise in the capillary tube 19, in accordance with well-known principles, until it finally touches the lower end of the wire 31, whereupon the circuit will be completed between the electrodes 23 and 26, thus affecting the operation of the apparatus with which the thermostat is connected.

The indicated circuit will be maintained so long as the external temperature does not fall below that corresponding with the lower end of the wire 31 and will be unaffected by a continuing rise in temperature above the minimum indicated. When the temperature does fall, however, a point will be eventually reached when the mercury in the capillary tube will fall below the lower end of the wire 31, whereupon the circuit will be broken between the electrodes of the thermostat.

The provision of the magnetic sleeve 27 and the magnet 33 affords a convenient method of placing the sleeve 27 in any desired position, while the length of the wire 31 within the capillary tube 19 provides for a convenient time lag in the operation of the thermostat, as may be desirable under certain conditions. For example, after the mercury has once contacted with the lower end of the wire 31, an additional rise of the external temperature does not affect the operation of the thermostat, nor does an ensuing drop in the temperature, following a rise above that indicated by the lower end of the wire 31, affect the instrument until the temperature drop is sufficient to cause a separation of the wire and mercury.

In Figs. 6 and 7, is illustrated a modified structure which may be employed in connection with the magnet 33 as a further means of securing adjustment of the thermostat. In this case a container 36, corresponding generally to the container 10, is provided at its lower end with a metallic diaphragm 37 in place of the glass, end wall 11. The diaphragm 37 closes one end of a lower chamber 38, corresponding to the chamber 14 and which is separated from an upper chamber 39 by a wall 40. Both chambers are provided with mercury pools in the manner above described and within the mercury pool in the chamber 39 is mounted an electrode 41 which is connected externally of the container by a lead-in wire 42. The diaphragm 37 functions as the electrode for the mercury in the chamber 38 and is connected externally of the thermostat by a wire 43.

The diaphragm 37 is composed of metal which will flex easily without undergoing crystallization and, in the form of apparatus shown in the figures under discussion, one end of an adjusting screw 44 contacts with the underside of the diaphragm 37 and is rotatably mounted in a convenient bracket arm 45. This screw may be composed entirely of an insulating material, or simply the end thereof which contacts with the diaphragm. The screw 44 may carry a pointer 46 which is arranged to sweep over a convenient scale 47 which is calibrated to denote an upward or a lowering movement of the diaphragm 37, corresponding to similar movements of the mercury in the chamber 38.

According to the foregoing arrangement, it will be understood that when the adjusting screw 44 is appropriately rotated to impart an upward flexing of the diaphragm 37, the mercury in the chamber 38 will rise in the associated capillary tube, while an opposite condition will be achieved by a contrary movement of the adjusting screw. Hence, it is possible by this mechanism to vary the initial or zero position of the mercury in the capillary tube and, in fact, to place such level above that which it would occupy for any given temperature condition. It is therefore possible with such an adjustment, in conjunction with the above-described adjustment of the sleeve 27, to lessen the time required for the mercury to contact with the wire 31, since it is entirely possible to initially place the mercury meniscus in the capillary tube at some point considerably higher than that corresponding to the external temperature. By appropriately operating the adjusting screw 44 and the magnet 33, the thermostat is capable of being adapted for service under a plurality of conditions, since it is possible to positively control the two variants in the structure, namely, the sleeve 27 and the level of the mercury meniscus in the capillary tube 19.

While I have shown one set of elements and combinations thereof for effectuating my improved thermostat, it will be understood that the same is intended for purpose of illustration only and in no wise to restrict the device to the exact forms and structures shown, for many changes may be made therein without departing from the spirit of my invention.

10 I claim:

1. A thermostat comprising a container divided by a wall into first and second mercury receiving chambers, said wall forming with said container a thermometer tube communicating with said first chamber, mercury pools in each chamber, an electrode immersed in the mercury in each of said chambers communicating with an external circuit, and a member contacting with the mercury in said second chamber and having a part extending into said tube, the rise and fall of the mercury in said tube in response to temperature changes determining the circuit condition through the thermostat.
2. A thermostat comprising a container divided by a wall into first and second mercury receiving chambers, a thermometer tube communicating with said first chamber, mercury pools in each chamber, an electrode immersed in the mercury in each of said chambers communicating with an external circuit, and a member contacting with the mercury in said second chamber and having a part extending into said tube, the rise and fall of the mercury in said tube in response to temperature changes determining the circuit condition through the thermostat.

3. A thermostat comprising a container divided by a wall into first and second mercury receiving chambers, a thermometer tube communicating with said first chamber, mercury pools in each chamber, an electrode immersed in the mercury in each of said chambers connected with an external circuit, and an adjustable member contacting with the mercury in said second chamber and having a part extending into said tube, the rise and fall of the mercury in said tube in response to temperature changes determining the circuit condition through the thermostat.

4. A thermostat comprising a container divided by a wall into first and second mercury receiving chambers, a thermometer tube communicating with said first chamber, mercury pools in each chamber, an electrode immersed in the mercury in each of said chambers connected with an external circuit, an adjustable member contacting with the mercury in said second chamber and having a part extending into said tube, the rise and fall of the mercury in said tube in response to temperature changes determining the circuit condition through the thermostat, and a part externally of the container for adjusting said

member and for holding the same in adjusted position.

5. A thermostat comprising a container divided by a wall into first and second mercury receiving chambers, a thermometer tube communicating with said first chamber, mercury pools in each chamber, an electrode immersed in the mercury in each of said chambers connected with an external circuit, an adjustable member comprising magnetic material contacting with the mercury in said second chamber and having a part extending into said tube, the rise and fall of the mercury in said tube in response to temperature changes determining the circuit condition through the thermostat, and magnetic means externally of the container for adjusting said member and for holding the same in adjusted position.

6. A thermostat comprising a container divided by a wall into first and second mercury receiving chambers, said wall forming with said container a thermometer tube communicating with said first chamber, mercury pools in each chamber, an electrode immersed in the mercury in each of said chambers connected with an external circuit, and a member slideable on the portions of said wall enclosing said tube for contact with the mercury in said second chamber and having a part extending into said tube, the rise and fall of the mercury in said tube in response to temperature changes determining the circuit condition through the thermostat.

7. A thermostat comprising a container divided by a wall into first and second mercury receiving chambers, a thermometer tube communicating with said first chamber, mercury pools in each chamber, an electrode immersed in the mercury in each of said chambers connected with an external circuit, a member contacting with the mercury in said second chamber and having a part extending into said tube, the rise and fall of the mercury in said tube in response to temperature changes determining the circuit condition through the thermostat, and means for varying the zero position of the mercury meniscus in said tube.

8. A thermostat comprising a container closed at one end by a diaphragm and divided by a wall into first and second mercury receiving chambers, mercury pools in each chamber, means for connecting said pools to an external circuit, a thermometer tube communicating with said first chamber, a member contacting with the mercury in said second chamber and having a part extending into said tube, the rise and fall of the mercury in said tube in response to temperature changes determining the circuit condition through the thermostat, and means for flexing said diaphragm to vary the zero position of the mercury meniscus in said tube.

9. A thermostat comprising a container

- closed at one end by a diaphragm and divided by a wall into first and second mercury receiving chambers, mercury pools in each chamber, an electrode located in the pool in said second chamber and said diaphragm acting as electrode for said first chamber, means for connecting said electrode and diaphragm to an external circuit, a thermometer tube communicating with said first chamber, a member contacting with the mercury in said second chamber and having a part extending into said tube, the rise and fall of the mercury in said tube in response to temperature changes determining the circuit condition through the thermostat, and means for flexing said diaphragm to vary the zero position of the mercury meniscus in said tube.
10. A thermostat comprising a container divided by a wall into first and second mercury receiving chambers, a thermometer tube communicating with said first chamber, mercury pools in each chamber, an electrode immersed in the mercury in each of said chambers communicating with an external circuit, an adjustable member contacting with the mercury in said second chamber and having a part extending into said tube, and means for varying the zero position of the mercury meniscus in said tube, the rise and fall of the mercury in said tube in response to temperature changes determining the circuit condition through the thermostat.
11. A thermostat comprising a container divided by a wall into first and second mercury receiving chambers, a thermometer tube communicating with said first chamber, mercury pools in each chamber, an electrode immersed in the mercury in each of said chambers connected with an external circuit, an adjustable member contacting with the mercury in said second chamber and having a part extending into said tube, a part externally of the container for adjusting said member and for holding the same in adjusted position, and means for varying the zero position of the mercury meniscus in said tube, the rise and fall of the mercury in said tube in response to temperature changes determining the circuit condition through the thermostat.
12. A thermostat comprising an hermetically sealed container internally divided by a wall into first and second mercury-receiving chambers, said wall forming with said container a thermometer tube communicating with said first chamber, mercury pools in each chamber, an electrode immersed in the mercury in each of said chambers, an inlead wire for each electrode sealed through the wall of the container and connected with an external circuit, and a member contacting with the mercury in said second chamber and having a part extending into said tube, the rise and fall of the mercury in said tube in response to temperature changes deter-

mining the circuit condition through the thermostat.

13. A thermostat comprising an hermetically sealed, glass tube internally divided by a wall into first and second mercury-receiving chambers, a thermometer tube communicating with said first chamber, mercury pools in each chamber, an electrode immersed in the mercury in each of said chambers, an inlead wire for each electrode sealed through the wall of the glass tube and adapted for connection with an external circuit, an adjustable member having magnetic characteristics contacting with the mercury in said second chamber, said member having a portion extending close to the inner wall of said glass tube and a part extending into said thermometer tube, the rise and fall of the mercury in said thermometer tube in response to temperature changes determining the circuit condition through the thermostat, and magnetic means located externally of the glass tube and adapted to coact with said member for adjusting and holding the same in adjusted position.

14. A thermostat comprising an hermetically sealed, glass tube divided by a wall into first and second mercury-receiving chambers, said wall forming with said container a thermometer tube communicating with said first chamber and having a bulged portion projecting into said second chamber, mercury pools in each chamber, an electrode immersed in the mercury in each of said chambers, an inlead wire for each electrode sealed through the wall of said glass tube and adapted for connection with an external circuit, and a member having a portion fitting closely around the bulged portion to confine the member to a sliding movement along the bulge, said member being arranged for contact with the mercury in said second chamber and having a part extending into said thermometer tube, the rise and fall of the mercury in said thermometer tube in response to temperature changes determining the circuit condition through the thermostat.

15. A thermostat comprising an hermetically sealed, tubular glass container internally divided by a wall into first and second mercury-receiving chambers, said wall forming with said container a thermometer tube communicating with said first chamber and having a bulged portion projecting into said second chamber, mercury pools in each chamber, and an electrode immersed in the mercury in each said chamber, an inlead wire for each electrode sealed through the wall of said container and adapted for connection with an external circuit, a member having magnetic characteristics provided with a portion fitting closely around said bulge to confine the member to sliding movements along the bulge, said member contacting with the mercury in said second chamber with a portion

extending close to the inner wall of said container and having a part extending into said tube, the rise and fall of the mercury in said tube in response to temperature changes determining the circuit condition through the thermostat, and magnetic means located externally of said container and adapted to coact with said member for adjusting and holding the same in adjusted position.

10 In testimony whereof, I have subscribed my name.

CARL J. WARNKE.
